UNITED STATES PATENT OFFICE.

JOHN C. GEBHART, OF ATLANTA, GEORGIA, ASSIGNOR TO ATLANTA
UTILITY WORKS, INC., OF EAST POINT, GEORGIA.

REVERSING TURBINE-ENGINE.

No. 829,396.

Specification of Letters Patent.

Patented Aug. 28, 1906.

Application filed January 11, 1906. Serial No. 295,615.

To all whom it may concern:

Be it known that I, JOHN C. GEBHART, a citizen of the United States, residing at Atlanta, in the county of Fulton and State of Georgia, have invented a new and useful Reversing Turbine-Engine, of which the following is a specification.

This invention relates to rotary engines, and has for one of its objects to provide an engine which may be quickly reversed and which is equally effective in both directions of movement.

A further object of the invention is to provide a novel form of rotary engine in which both the impact and pressure of the operating fluid may be utilized to the fullest advantage.

A still further object of the invention is to provide a rotary engine in which the piston wing or member on which the fluid acts is formed or carried by two adjacent revoluble members so connected that successive wings will be formed and presented opposite the inlet-port as said members revolve.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a sectional elevation of a rotary engine constructed in accordance with the invention. Fig. 2 is a transverse sectional view of the same on the line 2-2 of Fig. 1. Fig. 3 is a front elevation of the engine.

Similar numerals of reference are employed to indicate corresponding parts throughout the several figures of the drawings.

The main cylinder 10 is provided with a pair of movable end members or heads 11 and 12, and the main section 10 of the cylinder is divided into two chambers by a transversely-disposed partition 15.

The partition 15 and removable heads 11 and 12 carry bearings for four shafts 17, 18, 19, and 20, the axes of which are arranged at the four angles of a perfect square. These

shafts carry gears 21, all of said gears being of precisely the same construction and said gears intermeshing for the purpose of maintaining the pistons of the engine in proper relative positions and in order to transmit the power to one of the shafts, said shaft 19 being shown as extending through the head 12, and from this shaft motion may be transmitted to any machinery to be driven.

Mounted on the several shafts at points between the head 11 and the partition 15 are piston-drums 27, 28, 29, and 30, and these are provided with equidistantly-spaced peripherally-disposed wings 31, that are separated from each other by pockets of the peculiar form shown, said pockets being constructed to permit the exposure of the greatest possible area of the wings to the action of the fluid under pressure without waste in the quantity of fluid admitted. The wings 31 are maintained in proper relative position by the gears and are so arranged that two wings will come into engagement with each other and form a continuous wing extending directly across the pressure inlet-port, so that none of the pressure or the impact of the entering fluid will be wasted.

At the center of the several pistons is a valve-chamber 33, that preferably forms an integral part of the partition 15. The outer face of this valve-chamber is arranged on curved lines struck from the axes of the several shafts and is arranged to form fluid-proof joints in connection with the peripheries of the pistons which move over such surfaces.

Leading from the center to the outside of the valve-casing are two sets of ports 39 and 40, the ports 39 being diametrically opposed to each other and being arranged to permit the passage of jets of fluid under pressure in a horizontal direction between the several piston-drums. The ports 40 are diametrically opposed in a vertical plane and are arranged to direct jets of fluid under pressure in a vertical line between the several piston-drums.

Within the valve-casing is arranged a conical valve 41, having a pair of ports 42, which may be turned to allow the actuating fluid to pass through the ports 39 or the ports 40, in accordance with the direction in which the engine is to rotate, or the ports may be blanked, as shown in Fig. 1, in order to stop the engine.

Arranged between the several pistons are approximately triangular blocks 43, the opposite sides of which are curved to engage with the peripheries of the piston-drums, and 5 these serve to prevent the escape of the steam or other actuating fluid after one pair of wings separate and before wings of another pair come closely together.

Leading through the removable head 11 is 10 an inlet-port 44, the lower portion of which surrounds the outer portion of the valve 41, and the latter is provided with ports 45 in order to permit the free entrance of steam to the interior of the valve at all times. The 15 valve is held in place by a gland 46, which may be tightened by suitable bolts 47 in order to compensate for wear of the valve and prevent leakage. From the outer end of the 20 valve extends a stem 49, to which is connected a controlling-lever 50, and by turning this lever the engine may be started in either direction or may be stopped.

I claim—

1. In a rotary engine, four piston-drums, 25 the peripheries of which are provided with piston-wings arranged to engage each other, a steam-chest arranged at the center of the series of drums, ports leading from the chest on lines tangential to the drums, and a valve 30 for controlling the flow of steam through said ports.

2. The combination in a rotary engine, of 35 four piston-drums, gears connecting said drums in a continuous series, the peripheries of the drums being provided with piston-wings arranged to engage each other, a steam-chest arranged at the center of the series of drums, ports leading from the chest on lines 40 tangential to the drums, and a valve for controlling the flow of steam through said ports.

3. In a rotary engine, four connected and 45 contacting piston-drums provided with peripherally-disposed wings, and means at the center of the series of drums for directing jets of fluid under pressure between them.

4. In a rotary engine, four connected and 50 contacting drums having peripherally-disposed wings, a steam-chest arranged at the

center of the series of drums, ports leading from the steam-chest for directing jets of fluid 55 under pressure between said drums, and a valve for controlling the active ports and thus determining the direction of movement of the engine.

5. In a rotary engine, four connected and 60 contacting drums having peripherally-disposed wings, a steam-chest arranged at the center of the series of drums, and the outer surface of which is arranged on curved lines to follow closely the peripheries of the drums, 65 there being ports leading from the chest outward on lines tangential to the several drums, and an adjustable valve arranged within the chest for determining the active ports.

6. The combination in a rotary engine, of 65 four connected and contacting piston-drums having peripherally-disposed wings, a steam-chest arranged at the center of the series of drums and having ports on lines tangential to 70 said drums, and curved filling-blocks arranged to engage with the peripheries of the exhaust sides of the drums.

7. The combination in a rotary engine, of 75 a cylinder having an approximately central partition and provided with removable heads, a series of four equidistantly-disposed shafts 80 extending through the partition, a piston-drum mounted on each shaft, the peripheries of the drums being arranged to engage each other, gears arranged at the opposite ends of the shaft and intermeshing in a continuous train, one of said shafts being extended for the purpose of transmitting power, a valved and ported steam-chest arranged at the center of the series of piston-drums, and filling-blocks carried by the partition and arranged 85 to engage the peripheries of the exhaust sides of the drums.

In testimony that I claim the foregoing as my own I have hereto affixed my signature in 90 the presence of two witnesses.

JOHN C. GEBHART.
